SOFA BED
Norman J. Gran, 3130 N. Lake Shore Drive,
Chicago, Ill. 60614
Filed Apr. 11, 1966, Ser. No. 541,753
8 Claims. (Cl. 5—12)

ABSTRACT OF THE DISCLOSURE

This invention relates to a bed wherein the supports for the mattress are stringers extending from the head to the foot rails over which transversely extend flat flexible elastic bands so that a foam rubber mattress will be rigidly supported along parallel lines head to foot so as to eliminate all sagging without causing discomfort. The invention also relates to lowering one or more of the stringers in combination with a bolster whose face is parallel to the length of the bed so that a depression is provided in the foam rubber mattress much the same as one has in a couch.

This invention relates to an improved construction for a sofa bed, and includes an improvement in the construction of an ordinary bed.

This is a continuation-in-part of applicant's copending application Ser. No. 309,274, filed Sept. 16, 1963 for a Sofa Bed.

A sofa bed is one which has the configuration of a sofa for sitting purposes, i.e., a back support, and the sleeping area of a single bed for sleeping purposes. The back support of the sofa structure is obtained by providing a removable bolster, a rectangular pillow, or still better, by a removable bolster support and bolsters. Applicant's sofa bed was particularly designed to employ a mattress without the use of any supporting spring. Applicant's earliest sofa bed is shown in U.S. Letters Patent 2,894,266, dated July 14, 1959. In this patented construction, the mattress rests on a solid platform. This solid surface avoids sag but lacks cushioning. Longitudinal rigidity is particularly important.

The first object of this invention is to retain the rigidity of the mattress support while at the same time providing some cushioning effect. A feature of the present invention as applied to a bed is the provision of rigid stringers extending longitudinally of the frame. Flexible transverse bands upon which the mattress will rest are fastened along the front and back edges of the frame in the plane of the top of the stringers and are supported on these stringers. The stringers are spaced and the tensile strength of the bands chosen so as to provide the best cushioning qualities for sleeping. It is clear that there will be no center sag in any horizontal direction and this slight additional cushioning makes it possible to use a thinner mattress.

The second object of this invention is to provide an improved seat. A feature of this invention is means for lowering that stringer in the bed which is spaced from the front edge of the sofa by the average length of a thigh bone, i.e., the distance from the knee to the pelvis. When this stringer is in the lower position, the bands that support the mattress lose one of their rigid supports and the mattress along the line of that stringer is supported solely on the bands. This tends to thrust the sitter's back against the bolster and one sits more comfortably.

Another object of this invention as applied to a sofa bed is to connect a bolster support, such as that shown in applicant's above identified patent, to a driving means for lowering that particular stringer, or stringers, in the present construction so that when a sofa bed is used as a bed, the stringer will be automatically in its upper position, and when it is to be used as a sofa, that is, with the bolster support in position, the stringer will be in the lower position.

2

Two embodiments of the invention are presented in the accompanying drawings. In the first embodiment of FIGURES 1 through 6, only a single stringer is lowered out of the plane of the bands, and this stringer is positioned back from the front edge of the sofa at the point where one ordinarily sits. The second embodiment of the invention is the preferred embodiment and shows all of the stringers lowered when the sofa is to be used as a couch, those stringers toward the longitudinal center of the frame being lowered the most.

Other objects and uses of the instant invention will become readily apparent to those skilled in the art upon a perusal of the following specification in light of the accompanying drawings in which:

FIGURE 1 is a perspective view of a convertible sofa bed in an attitude for use as a piece of furniture for sitting upon;

FIGURE 2 is a perspective view of the sofa bed shown in FIGURE 1, but with bolsters removed, the bolster support folded back and the side panels swung open;

FIGURE 3 is a fragmentary perspective view of a frame portion of the sofa bed shown in FIGURE 1;

FIGURE 4 is a cross-sectional view of the sofa bed shown in FIGURE 1 showing a longitudinal stringer displaced to provide additional comfort for the sofa bed when used for sitting;

FIGURE 5 is a cross-sectional view similar to FIGURE 4 but with the sofa bed shown in an attitude for sleeping;

FIGURE 6 is a fragmentary perspective view of one end of a base frame portion showing a mount for a pivotal longitudinal stringer;

FIGURE 7 is a portion of a cross-sectional view taken on line 7—7 of FIGURE 5 showing a portion of a mechanism for operating the pivotal longitudinal stringer;

FIGURE 8 is a perspective view of a preferred embodiment of the invention;

FIGURES 9 and 10 are views, partly in section, taken along the lines 9 and 10 of FIGURE 8 respectively, and showing the position of the stringers in the bed position, FIGURE 9, and the position of the stringers in the sofa position, FIGURE 10; and

FIGURE 11 is a view taken along the line 11—11 of FIGURE 9.

Referring now to the drawings, a sofa bed, generally indicated by numeral 10, is shown in FIGURES 1 and 2. This is the first embodiment of the invention. The sofa bed generally includes a base frame 14 for supporting a mattress. A bolster frame 12 is mounted on the back of the base frame. A mattress 16 is positioned on the base frame 14, and a bolster support 18 is pivotally mounted on the bolster frame 12. Three bolsters 20 are removably positioned on the mattress 16 and supported in a substantially upright position by the bolster support 18.

The bolster frame 12 includes a pair of identical sides 26 and 28. The bolster support 18 includes a top panel 30 which is connected to the bolster frame 12 through hinge 32. A bolster panel 34 is connected at one edge to one edge of the top panel 30 through hinge 36. A pair of end walls 22 and 24 are mounted on hinges not shown which are mounted on the side members 26 and 28. These can be opened to an angle of about 45° as suggested in FIGURE 2.

The base frame includes a pair of longitudinal side bars 38 and 40 which are connected to each other by end bars 42 and 44. Four legs 46 are connected at the four corners of the base frame to provide a vertical support for the instant device. An end brace 48 connects one pair of legs while a second end brace 50 connects the other pair of legs as may be seen in FIGURE 3. An interior brace 51 connects the side members 38 and 40 of the base frame. The brace 51 has an offset 53 for reasons which will become apparent hereinafter. A plurality of longitudinal

stringers 52, 54, 56 and 58 is mounted between the end members 42 and 44. The longitudinal stringers 52, 54 and 58 are fixed in position, whereas the stringer 56 is pivotally mounted to provide a disengageable support means for the mattress. Perpendicular to the stringers is a plurality of spring bands 60 each of which is identical in construction to each other, and each of which is fixed in respective apertures 62 in the longitudinal members 38 and 40. The mattress 16, which is conventional in construction, rests on the plurality of spring bands 60.

It should be noted that stringers 52 and 54 co-operate to provide a first permanent mattress-supporting surface. Stringer 58 provides a second permanent mattress-supporting surface. The two permanent mattress-supporting surfaces are separated by a space occupied by stringer 56. It is evident that when the stringer 56 is in an "up" position, there is a substantially continuous mattress support. When stringer 56 is in a "down" position, there is a space between the permanent mattress-supporting surface which allows the mattress to sag slightly when a load is applied.

Looking now to FIGURE 3, it may be seen that the longitudinal stringer 56, as do the other stringers, has a curved engaging surface 64, which is engageable with the spring bands 60. The stringer 56 has one end pivotally mounted in a boss 66 which is fixed to a vertical post 68 between brace 50 and end member 42. The other end of the stringer 56 is connected to a means for selectively tilting the stringer to a down position out of engagement with the bands 60.

A tilting device 70 is connected to the stringer 56 and the bolster support 18. The tilting device includes a slotted arm 72 which is fixed to the stringer 56. The slotted arm has a pin 74 extending therefrom which is pivotally mounted in a bearing 76. The bearing 76 is in turn fixed to a vertical post 78 which extends between and is fixed to the end member 44 and the brace 48. The slotted arm contains a slot 80 which has slideably mounted therein a pin 82. The pin 82 is in turn fixed to a pivot arm 84 which arm 84 is pivotally mounted on the brace 48, through a pivot pin 86. A tension spring 88 is connected to the pivot arm 84 and to one of the legs to urge the arm away from the bolster support. A cable 90 has one end fixed to the pivot arm 84 and the other end is connected to the bolster support. The cable is in permanent engagement with a sheave 92, which is rotatably mounted on the end member 26. The end of the cable 90 is fixed to the top panel 30 adjacent to one edge thereof. Although only one tilting device is shown herein, it is evident that there may be a tilting device at each end of stringer 56, if it is so desired. It should be noted that the tilting device is so arranged that stringer 56 is locked into an "up" position once the position is attained. The stringer 56 may be moved to a "down" position only by proper manipulation of the bolster support. This feature is important in that it prevents the stringer 56 from being tilted by movement of a person on the mattress.

A bedding bar 96 is pivotally mounted on the base frame between the end members 26 and 28. The bedding bar includes an axle 98 with a pair of offset arms 101 and 103 fixed to the axle. A rod 105 is fixed to the ends of the arms 101 and 103. It may be seen that the arms 101 and 103 have an offset to accommodate the mattress 16.

Looking now to FIGURE 4, it may be seen that when the sofa bed 10 is used as a sofa, the longitudinal stringer 56 is in a down position, that is, the stringer 56 does not engage the spring bands 60 to provide support for the mattress. Thus, when a person sits on the mattress 16, the person sinks down to a low position in the rear or back portion of the seat cushion which is the mattress. The stringer 58 with the side member 38 provides increased support in the front part of the seat cushion, so that a person sitting on the mattress has a feeling of being tilted back toward the bolsters 20. A person sitting on the sofa

bed is in a comfortable attitude in that he does not have the feeling of slipping forward and off the sofa.

It may be noted that the bolster panel 34 is in a down position above the mattress and the bolsters 20 are against the bolster panel when the device is used as a sofa. It may also be seen that a cabinet is formed by the top panel 30 and the bolster panel 34 so that bedding and pillows may be placed in the cabinet formed by the bolster support. The bedding is mounted on the bedding rod 96 and stored conveniently in the bolster support.

When it is desired to convert the sofa bed from a sofa to a bed, it is a simple matter to do so. The bolsters 20 are first removed. The bolster panel 34 is swung on hinge 36 to fold the panel 34 against top panel 30. The top panel is then pivoted about hinge 32 to a vertical attitude, such as that shown in FIGURE 5. This operation removes the bolster support from a position above the mattress 16. At the same time that the top panel 30 is pivoted about hinge 32, the pivoting of this panel brings the connector 94 down toward the sheave 92 so that the cable 90 is released relative to the pivot arm 84. The spring 88 pulls the arm in a clockwise direction as viewed in FIGURES 4 and 5. The pivoting of the arm causes the slotted arm 72 to pivot which in turn pivots the longitudinal stringer 56 until the stringer attains a vertical attitude or up position in supporting engagement with the bands 60 as are the other longitudinal stringers.

With the bolster support out of the way, the bedding arm may be moved about its axle 98 so that bedding folded over the bedding rod 105 may be placed on the mattress 16. It may be seen how it is a simple matter to unfold bedding onto the mattress. The pillows are positioned on the bedding and the bed is ready for use after the bedding arm is rotated back to its vertical position as shown in FIGURE 5.

It may be appreciated that the mattress 16 provides a substantially flat surface for a user. The longitudinal stringers provide adequate support to support a person resting upon the mattress. It may also be noted that the loading on the longitudinal stringer 56 is such that it does not tend to pivot in either direction in view of the fact that the force is down and in line with the rod 74 and the tilting device locks the stringers 56 in an up position.

After the instant device has been used as a bed, it may be readily converted to a sofa by first bringing the bedding arm 96 down and folding the bedding over the rod. The arm is then raised to a vertical attitude, thus revealing the mattress. The top panel 30 is pivoted about its hinge 32 so that the pivot arm 84 is pulled in a counter-clockwise direction against the force of spring 88, thereby pivoting slotted arm 72 in a clockwise direction along with longitudinal stringer 46 to disengage the stringer from the bands 60 and thus remove support for the mattress. The bolster panel 34 is brought down about hinge 36 to engage the mattress, and the bolsters 20 are positioned against the bolster panel. The device is then ready for use as a conventional sofa in the manner described above.

Attention is invited to the spacing of the stringers 54, 56 and 58. Stringer 56 is spaced from the front edge of the sofa bed by the average distance between the inside of the knee and the center of the pelvis. Stringer 56 is centered between stringers 54 and 58 which are spaced by about 14 or 15 inches. As shown in FIGURE 4, when stringer 56 is in lower position, any weight above that stringer will be supported solely by the bands. The bands are not fastened to the stringers, but preferably only at their ends. In a case where it was found desirable for sleeping position, to position the stringers at half the distance, thus placing a stringer between 54 and 56 and another between 56 and 58, applicant will lower all three stringers in order to obtain the desired comfort for a sitter. It will be appreciated that the

number of stringers, and their spacing, necessarily must be a function of the flexibility or elasticity of the bands and of the particular mattress with which the sofa is to be equipped. Lowering longitudinal supports for a mattress, with or without bands, along a line spaced from the front edge of a sofa may be effected in various ways.

The second embodiment of the invention is shown in FIGURES 8 through 11. Herein the stringers 100, having rubber buffers 102, are mounted longitudinally on angle irons 104 and 106, and 108 and 110. Referring to FIGURES 9 and 11, the angle iron 104 is pivoted at 112, and the angle iron 108, at 114. The angle irons 106 and 110, see FIGURE 8, at the other end of the bed are similarly pivoted. Engaging the horizontal bottom surface 116 of the angle iron 104, see FIGURE 11, is a roller 118 rotatably mounted on shaft 120 carried by an arm 122 keyed to a shaft 124 extending the entire length of the bed and approximately centered in the frame 14. This shaft 124 is rotatably mounted on the base member 125. This arm 122 is keyed to the shaft 124 so that rotation of the arm 22 or the shaft 124 will cause similar rotation at the far end, referring to FIGURE 8, on the frame 14.

When the arm 122, referring to FIGURE 9, is in the vertical position as shown in FIGURE 9, the angle iron 104 is horizontal so that the top of the stringers 100 and 102 are in substantially in the plane of the top of the side rails 126 and 128. The angle iron 108 is held in the same plane because a tongue 130 projects forwardly from the angle iron 104 and engages the underside 132 of the horizontal portion of the angle iron 108. The angle iron 104 has a stop 134. Normally, a bail 136 connected to a contracted spring 138 anchored to the support 140 holds the arm 122 in a vertical position.

Also anchored to the arm 122 is a cable 142 which is belayed over a sheave 144 and anchored to a bracket 146 on the panel 148.

In FIGURE 9, the sofa bed is shown in bed position. The panel 148 is raised, see also FIGURE 8, so that the air space above the entire bed is clear. In this position (the spring 138 holds the arm 122 in the position shown so that the stringers 100 have their top surfaces in a horizontal plane with the bands 150 above them.

When, however, one wishes to convert the bed into a sofa, the bed clothing is tossed over the bedding bar and the two panels 148 and 149 are swung into the position shown in FIGURE 10. In so doing, the cable 142 draws the arm 122 into the position shown, thereby allowing the rails 104 and 108 (and the complementary parts at the other end of the bed) to drop below the level of the bands 150. If no one is sitting on the sofa, the bands are sufficiently strong to hold the mattress 152 level, thus giving the nice appearance shown in FIGURE 1. When, however, a person sits on the sofa, the bands stretch until they rest upon the cushion members 102 and a proper seat is obtained. It will be appreciated that the extent of the descent of the support rails 104 and 108 may be varied, and will be in the case of beds which are narrower than the one shown. Also, the bands provide more support as they are stretched.

Although two specific embodiments of the herein disclosed invention have been shown and described in detail above, it is readily apparent that those skilled in the art may make various modifications and changes without departing from the spirit and scope of the present invention. Thus, some models of the design shown in FIGURES 1-7 have been in use for about two years, and surprisingly the under side of the bands adjacent the stringer 64 are showing wear because the stringer is rotated out of position. Raising the stringer vertically would eliminate this objection and could readily be done.

Also, in the models employing the second embodiment of the invention, FIGURES 8 through 11, it may turn out to be more desirable to mount just the two inside stringers on the rails and fix the two outside stringers to the foot and head rails of the rectangular frame. For convenience in claiming, referring to FIGURES 3, the rail 44 is referred to as the "front rail," the rail 42 as the "foot rail," and the rails 38 and 40 as the "side rails." It is to be expressly understood that the instant invention is limited only by the appended claims.

I claim:

1. A bed comprising a rectangular frame having foot, head and side rails, a plurality of substantially rigid, spaced, parallel stringers supported at opposite ends on adjacent the foot and head rails, the upper surfaces of the stringers being substantially in a common plane, and a plurality of closely spaced, flexible bands fastened at their opposite ends to the side rails and supported by said stringers and free to slide thereover.
2. The bed of claim 1 wherein the flexible bands are parallel to each other.
3. A sofa bed consisting of the bed of claim 1 together with a back support extending along and above the bands on one side of the frame, and means for lowering below the plane of the bands one of the stringers intermediate the side rails.
4. The sofa bed of claim 3 together with means for moving the back support from a position above the bands and a drive train interconnecting the back support and the lowering means whereby moving the back support away from a position over the bands actuates the lowering means to restore the lower stringer to its upper position.
5. The sofa bed of claim 4 wherein the lowering means is held in its upper position by a spring, wherein the back support is pivoted on a longitudinal axis so that it may be swung away from a position above the frame, and wherein the drive train is a cable held taut between the lowering means and the back support.
6. The sofa bed of claim 4 wherein the lowering means includes the mounting of the stringer on pivots whose axes are normal to a line between foot and head rails and which are positioned beneath the top of the stringer so that the stringer may be rotated below the bands.
7. A sofa bed consisting of the bed of claim 1 wherein two angle irons are positioned intermediate the foot rail and the stringers, said angle irons being parallel to the foot rail and pivoted thereto at their outer ends with the adjacent ends of the stringers mounted on these rails, the ends of the stringers adjacent the head rail being similarly mounted on similarly pivoted angle irons, and means for raising and lowering the free ends of the angle irons.
8. A sofa bed comprising a rectangular frame having foot, head and side rails, a plurality of substantially rigid, spaced, parallel stringers supported at opposite ends adjacent the foot and head rails, the upper surfaces of the stringers being substantially in a common plane, flat, flexible means stretched over said stringers and fastened along each side to one side rail, and means for lowering below the plane of the flexible means one of the stringers intermediate the side rails.
